MACHINE FOR ABRADING PHOTOENGRAVING CYLINDERS

Frank E. Yetter, St. Louis, Mo., assignor to The Pulitzer Publishing Company, St. Louis, Mo., a corporation of Missouri

Application October 21, 1937, Serial No. 170,200

6 Claims. (Cl. 51—142)

The present invention relates to a novel method and means of obtaining a desired finish on photoengraving cylinders, and the like.

It is well recognized that to obtain a desirable reproduction by photoengraving cylinders, it is necessary that the outer coating or surface be microscopically smooth. Otherwise, blemishes in such surface will produce faults in the pictures obtained from the cylinder. Heretofore the practice in putting the final polish on the cylinders has involved the use of a rotating disc of an abrasive material carried over the cylinder by a moving head, while the cylinder rotates. Inevitably, such a rotating head produces intersecting abrasive lines on the surface. These intersections entrap ink when the cylinder is later used, which ink prints out in the final picture to produce a flaw therein.

The present method comprehends abrading the cylinder in such wise as to void such intersecting abrasive grooves. More particularly, it produces grooves, if any, that are unidirectional and so related to the surface of the cylinder as not to entrap any ink when the cylinder, after engraving, is rotated against the cleaning knife. This method is effected by means of an endless belt abrasive that is caused to pass across the surface of the cylinder and simultaneously to be carried axially thereof. The result is that any abrasive lines that appear in the surface all occur approximately at right angles to any generatrix of the surface and are generally in a spiral on the surface.

It is a primary object of the invention to provide a method of polishing photoengraving cylinders in such wise as to minimize the production of abrasive scoring, and to avoid the presence of any intersecting abrasive lines. More specifically, it is an object to provide a method wherein any abrasive lines will be unidirectional and transverse to a generatrix of the cylinder.

A further object is to provide a method of the kind described, including a buffing operation wherein any abrasive lines are automatically filled in by the material on the surface of the cylinder.

A further object of the invention is to provide a mechanism for producing the above method in a most advantageous form, which mechanism includes an endless belt abrasive with means to move the same substantially transversely to a generatrix of the cylinder. It is further an object to produce relative movement between the moving belt and the cylinder axially of the cylinder.

It is a further object of the invention to provide means to adjust the tension of the belt and also to provide means to adjust the degree of contact between the belt and the cylinder surface.

It is a further object of the invention to provide a belt that will at least substantially eliminate any edge produced abrasive lines and a further object is to provide buffing belts of unique characteristics for use in producing an absolutely smooth surface.

Other objects will appear from the drawings and description to follow.

In the drawings:

Fig. 1 is a plan view of the mechanism;

Fig. 2 is an end view taken from the right of Fig. 1;

Fig. 3 is an end view taken from the left of Fig. 1 and showing the device partly in section;

Fig. 4 is a section on one of the abrasive head rollers taken on the line 4—4 of Figs. 2 and 3;

Fig. 5 is a broken section through the abrasive head taken on the line 5—5 of Fig. 1;

Fig. 6 is an enlarged view of a contact adjusting mechanism partly in section;

Fig. 7 is a section on the line 7—7 of Fig. 6 showing a retaining device;

Fig. 8 is a section on the line 8—8 of Fig. 6 through one of the surface contact adjusting mechanisms;

Fig. 9 is a section on the line 9—9 of Fig. 6 giving an end view of one of the surface contact adjusting mechanisms;

Fig. 10 is a section of one of the surface contact adjusting mechanisms taken on the line 10—10 of Fig. 6;

Fig. 11 is a section through one of the abrasive head rollers taken on the line 11—11 of Figs. 1 and 2;

Fig. 12 is a vertical section on the line 12—12 of Figs. 1 and 3 showing the height adjusting mechanism;

Fig. 13 is a detail showing of the height adjusting mechanism being a section on the line 13—13 of Fig. 12;

Fig. 14 is a view of the gear reduction drive for the mechanism;

Fig. 15 is a view of the buffing belt; and,

Fig. 16 is a sectional view thereof taken on the line 16—16 of Fig. 15.

The machine includes an elongated bed or base 20 adapted to rest on a suitable foundation, such as the floor. This bed has upstanding end portions connected by suitable front and rear braces, the end portions being provided with journal

supports 21 to which are pivoted as at 22 complementary journal arms 23. The supports 21 and the arms 23 provide journals 24 to receive an axle 25 of a photoengraving cylinder 26. With both of the arms 23 turned up to open the journals, the cylinders may be rolled into position with the main part of the cylinder between the ends of the bed, after which the arms 23 are pivoted down to close the journals and are secured in position by screws 27.

At its back side the bed 20 has an upstanding track 30 thereon, the track being dovetailed on one edge, as shown in Fig. 5. This track receives a supporting runner 31 of the abrading head, which runner is dovetailed to correspond with the front edge of the track 30, and is secured at the back edge of the track by a plate 32 bolted thereto as shown in Fig. 5.

The track 30 is provided with an elongated opening 33 terminating short of the ends thereof. Each of the opposite ends of the track has a bearing 34 thereon medially located beneath the opening 33. A lathe screw 35 is journaled within the bearings 34 and extends completely through one of them, as shown in Fig. 1.

The cylinder axis 25 extends beyond one of the journals 24 and has removably keyed thereto a gear 38. Beneath this gear 38 there is journaled a gear 39 (Fig. 14) meshing therewith, that in turn meshes with the drive gear 40 secured to a suitable power source. The power source thus drives the cylinder gear 38 through the intermediate idler 39. A second idler 41 meshes with the idler 39 and is journaled to the bed 20. The idler 41 in turn meshes with the third idler 42 mounted upon the base 20, which idler has rotating therewith a worm 43. The worm 43 meshes with a worm gear 44 mounted on a bearing 45 on the bed. In the particular arrangement here shown, the bearing 45 is a vertical journal and supports a countershaft 46 to which the worm gear 44 is secured. At the top of the shaft 46 a bevel gear 47 is mounted, this gear, therefore, receiving through the gear train power from the motor driven gear 40.

A pair of reversing bevel gears 48 and 49 (Figs. 14 and 1) are both secured to the lead screw 35. In the manner usual to the art, the two gears 48 and 49 are parts of a reversing clutch operated in the usual manner in lathes to reverse the direction of rotation of the head screw as the carriage is brought to each end of its travel. Details of this reversing mechanism are not shown.

The carriage runner 31 has a depending internally threaded boss 50 thereon extending into the opening 33 of the track member 30. The boss 50 receives the head screw 35 whereupon the runner 31 is caused by the screw to reciprocate back and forth across the bed.

A more or less U-shaped flanged plate 55 is bolted as at 56 to the runner 31. The upper surface of the plate 55 has a circular opening 57 therein (Figs. 5 and 11) that receives a corresponding circular boss 58 on a head support 59. A clamp element 60 extends in from the bottom of the hole 57 and is bolted into the circular boss 58 by screws 61. As is shown in Fig. 11, a small space exists between the clamping element 60 and the boss 58 so that the binding effect in this connection may be adjusted. The connection permits rotary adjustment of the support 59 and normally is sufficiently tight to hold the support 59 to the head elements thereon in adjusted position while permitting them to be moved manually.

The plate 59 extends laterally to overhang the

bed of the machine beyond the limits of the plate 55. The plate is divided by a vertical supporting wall 64.

The belt supporting mechanism includes a frame formed primarily of two pieces 65 and 66 bolted together. The member 65 is essentially a side wall to this frame, whereas the member 66 includes, not only the complementary side wall for the other side thereof, but also a connecting web 67 having spaces 68 therein to reduce the quantity of metal. Bolts 69 extend through the member 65 and into flanges 70 (dotted lines Fig. 3) depending from the connecting web 67 of the member 66 whereby to secure the two together as an integral unit.

The member 65 at its inner end extends over the support 59 adjacent the wall 64. The wall is provided with a central opening 71, around which on one side is a circular bearing surface 72, and spaced therefrom an additional arcuate bearing surface 73 extending approximately three-quarters of the way around the opening as shown in Fig. 3. The wall 64 has spokes projecting between the surfaces 72 and 73, these spokes being integral with the wall, as are shown in Fig. 3. On the face of the wall 64 opposite the aforementioned surfaces, there is a short arcuate shelf 74, terminating at one end in a stop-shelf 75 for a purpose to be described.

The end of the member 65 is flanged, as shown at 76 and 77, the latter having an arcuate extension (Fig. 3). The flange 77 extends slightly over the opening 71 and has a lateral wall flush with the bearing surface 73. Therebeyond, the member 65 extends inwardly along an edge 78 to an arcuate portion 79 that rests within the arcuate shelf 74. The member 65 also has a circular boss 80 that fits in bearing relation within the opening 71 of the wall 64.

A substantially arcuate dished clamping plate 81 fits over the wall 64 opposite the member 65. This plate 81 has an arcuate portion 82 screwed to the arcuate portion of the flange 77 by screws 83. The plate 81 has a circular boss 84 fitting within the opening 71 opposite the boss 80 on the frame member 65. Around this boss it is provided with a circular bearing surface to cooperate with the surface 72 on the wall 64, and an arcuate bearing surface to cooperate with the bearing surface 73. It will be observed that the arcuate extent of the surface 73 is somewhat greater than the plate 81.

Screws 85 extend through the plate 81, its boss 84, and into the boss 80 of the frame member 65. A space between the two bosses permits the bolts to be tightened as necessary to hold the parts together, but with enough freedom to allow the frame 65 to be swung upwardly about the wall until the edge 78 strikes the ledge 75. Preferably this movement is somewhat over 90°, so that the frame will rest in its lifted position. In this movement the plate turns on the surfaces 72 and 73, and the member 65 turns about the opposite face of the wall 64, with the arcuate portion 79 of the frame riding on the arcuate ledge 74.

A motor 86 is mounted on the support 59 outside of the wall 64. This motor has a shaft 87 extending through central bores in the plate 81, and the frame member 65, and through the opening 71. A frictionless bearing 88 in the boss 84 supports the shaft. An additional bearing 89 in the frame member 66 supports the other end of the shaft. Between the frame members a roller 90 is keyed to the shaft 88. A resilient outer cover 91 surrounds the roller.

The member 59 is provided with a pair of ears 92 extending from one edge thereof. A threaded sleeve 93 is pivoted at 94 between the two ears. A threaded rod 95 is received into the sleeve 93. This rod extends through the member 65 to the top thereof above the flange 76, and has turning handles 96 secured to its upper end. The flange 76 of the member 65 has an internally threaded boss 97 at the place where the rod 95 extends therethrough. The rod 95 has on it a ball section 98 located within the threaded boss. Complementary caps 99 and 100 are extended into the threaded boss against the ball section 98 and are secured therein by set screws as shown. Kerfs are provided in the bearing cap elements for their manipulation. The two bearing caps engage the ball section to provide a supporting means to maintain the position of the frame as it is pivoted about the wall 64. As is evident, rotation of the handles 96 by the threaded engagement between the rod 95 and the sleeve 93 raises or lowers the frame about the wall 64.

At the outer end of the frame, there is provided a shaft 103, which shaft is mounted in block-shaped bearing boxes 104, there being one such box for each side of the frame. The bearing boxes 104 are supported on slides in openings 105 in the sides of the frame wherein they may move axially of the frame. Each bearing box has a threaded extension 106 passing through a flange 107 of each of the sides of the frame. A pair of nuts 108 are mounted on the extensions 106 whereby to limit the inward movement of the axle 103 and to lock the adjustment. Thus, each end of the axle may be adjusted separately within the limits of the lost motion of the mountings.

A tension adjusting means is provided in the form of three rollers conveniently located adjacent the outer roller 102. This means includes opposite brackets 110 mounted on the frame members 65 and 66 and supporting between them an idler roller 111. Similar brackets 112 support an idler roller 113 spaced a short distance from the roller 111. Between these two rollers, there are provided spaced brackets 114 having dovetailed vertical slots in them as shown. Supporting members 115 are held to slide vertically within the slots. A tension roller 116 is mounted between the members 115. Adjacent the bottoms of the slots of the brackets 114 are horizontal ledges 117 through which are threaded screws 118 that abut corresponding ledges 119 on the elements 115. Thus, adjustment of the screws 118 elevates or lowers the roller 116. Lock nuts are provided on the screws to hold them in adjusted positions.

Mechanisms consisting of a pair of horizontally and vertically adjustable rollers are also provided for adjusting the area of contact between the belt and the cylinder. On each of the side members 65 and 66 there is secured a track member 122. Each track member is dovetailed, as shown in Fig. 10, to provide horizontal runners.

A pair of rollers 123 and 124 are mounted on the slides 122. The rollers are supported in mechanisms providing for vertical and horizontal adjustments, and these mechanisms are all similar save that the two on each side are opposite to each other. Consequently, a description of one mounting will suffice for all.

The roller 123 has a resilient outer covering 125. It is supported upon an axis 126 that in

turn is received in opposite bearing blocks 127 joined by a connecting bar 128. Each bearing block has a threaded rod 129 extending upwardly from it, the rods being surrounded by coil springs 130. The rods 129 extend through ledges 131 on vertically adjustable slides 132 and nuts 133 are located above the ledges to secure the rods. The bearing blocks are guided toward the bottom by walls 134 also on the vertical slides 132. Thus, the bearing blocks may be individually drawn up or let down by adjustment of the nuts 133 which changes the tension of the springs 130.

The slides 132 are dovetailed to engage in corresponding tracks 135 in horizontally adjustable slides 136. The vertical slides likewise have openings 137 in them, one edge 138 of which is formed as a rack. A shaft 139 is journaled in the opposite horizontal slides 136 and extends completely across and outside both sides of the frame. This shaft 139 extends through both openings 137 and within them has gears 140 secured to it. These gears mesh with the racks 138. Handles 141 are secured to the opposite projecting ends of the shaft 139 for the purpose of turning the shaft. From the foregoing it will be seen that turning either handle 141 rotates the shaft 139, turning both gears 140 and simultaneously adjusting both of the vertical slides 132 to which is secured the roller 123.

The horizontal slides 136 are dovetailed to ride upon corresponding dovetails of the main tracks 122. The upper edges of the horizontal slides 136 are formed into racks 142. A shaft 143 is journaled in the members 65 and 66 of the frame and extends completely across and through these sides. Outside of the two side members gears 144 are secured to mesh with the racks 142 on the horizontal slides. Handles 145 are secured to opposite ends of the shaft 143. Thus, rotation of either handle 145 rotates the shaft 143 and both gears 144 to shift both horizontal slides 136. Necessarily the vertical slides are carried with the horizontal slides, being mounted on them. In order to accommodate for the horizontal displacement of the shafts 139 upon movement of the horizontal slides, slots 146 are provided in the side members 65 and 66 of the frame.

The adjusting mechanism for the roller 124 is identical with that for the roller 123, but is arranged oppositely thereto. In connection with the roller 124, in Fig. 6, are shown lock means for the several adjustments. The vertical slide 132 at one edge is provided with a series of openings 147. A plate 148 is secured to the horizontal slide (Fig. 8) and overlies the edge of the vertical slide containing the holes 147. To the plate 148 are secured opposed ears 149 between which is pivoted a lever 150. This lever has pivoted to one of its ends a pin 151 that passes through a hole in the plate 148 and may selectively be engaged in any of the holes 147. A spring 152 located between the plate 148 and the other handle end 153 of the lever 150 maintains the pin 151 inwardly into engagement with one of the holes 147. The pin may be freed by depressing the handle end 153 of the lever. It will be seen that adjustment by rotation of the handles 141 may be had only after the pins 151 are freed. Of course, it is necessary to have this lock on only one side in view of the rigid connection effected by the shafts 139 and their several gears.

For locking the horizontal slides there are mounted on the member 66 a pair of spring blades 155. Each blade 155 has a pin 156 extending

through the flange on the member 66 and engageable between teeth on the gears 144. The spring blades 155 normally urge the pins 156 out of engagement with the gears 144. However, the free ends of the spring blades are forked as at 157 and surround screws 158. Nuts 159 are engaged over the screws 158 and may be threaded down to force the spring blades correspondingly down to put the pins 156 against the gears 144.

The belt 165 is shown in Fig. 1 to have an irregular edge. This edge is more or less scalloped to avoid the scarring action of a straight edged belt. A buffing belt, such as in Figs. 15 and 16, may be used. It preferably is of a leather base part 167 to which are secured a series of spaced pads 168 of felt or like material. The pads are so arranged as to be out of contact with each other, but to overlap.

The operation of the mechanism is as follows:

The frame is turned up about its pivot including the boss 80 engaging in the opening 71 in the wall 64 until stopped by engagement of the edge 78 with the ledge 75. The bearing brackets 23 are opened and the cylinder 26, duly coated with copper but unpolished, is shifted into position within the bearing blocks 21. The arms 23 are then closed down and secured into position by the screws 27.

The frame then is turned down over the cylinder and the rod 95 engaged into the sleeve 93 controlling the limit of the downward movement of the frame and providing for a fine adjustment thereof. The entire frame is then adjusted manually about its pivot at 58 to a proper angular position relative to the axis of the cylinder, which may be perpendicular thereto, as shown in full lines of Fig. 1, or may be at some angle thereto, as shown in dotted lines in that figure. The angular position reduces whip in the belt and increases the area of contact.

In order to compensate for any inequalities in the length of the belt between its two sides, the nuts 108 are adjusted individually to draw the bearing blocks 104 out until the tension is the same across the belt. The tension of the belt also may be controlled by adjusting the screws 118 to lift the roller 116 of the belt tensioning mechanism.

The area of contact of the belt with the cylinder is determined in part by the adjustment of the handles 96 that raise and lower the entire frame relative to the cylinder. Following this adjustment, the lock pins 156 are released, and the handles 145 are turned, shifting the horizontal slides inwardly or outwardly, as the case may be, which properly places the rollers 123 and 124 preferably equally spaced on opposite sides of the axis of the cylinder, and also places these slides in proper position for adjustment of the vertical slides by the handles 141. After this, the nuts 159 are turned down to force the pins 156 against the gears 144. The lock pins 151 are released by depression of the handles 153 and the handles 141 are turned to raise or lower the rollers. The lock pins 151 are then permitted to engage in the adjacent holes 147. As is perfectly evident, these two adjustments determine the area of contact between the belt and the cylinder.

The motor driving the power gear 40 is then started to cause the gear 38 to be rotated, driving the cylinder at a proper speed and, at the same time, the gear 40 produces rotation of the screw 35 that, through engagement with the depending member 50 of the runner 31, moves the entire head in one direction or the other axially of the

cylinder. It is, of course, understood that at the end of each reciprocation of the head to one end of the cylinder, the screw 35 is automatically reversed in the manner well known in the art and suggested in Fig. 14, so that the head is then moved in the other direction toward the other end of the cylinder.

The motor 86 is put in operation at this time and may be connected so as to be energized simultaneously with the energization of the source of power driving the gear 40. The motor 86 causes rotation of the shaft 87, which shaft, being keyed thereto, drives the roller 90 about which the belt travels. The belt then travels about the roller, through the tension mechanism, about the roller 102, beneath the rollers 123 and 124, and over the cylinder 26. Preferably the speed of operation of the motor 86 is relatively high, being in the neighborhood of 4000 R. P. M.

With the belt thus in motion, the abrasive action is manifestly unidirectional and substantially perpendicular to the generatrix of the cylinder 26. The rotation of the cylinder, of course, distributes the polishing action completely around the surface and the reciprocal movement of the head by the screw 35 distributes this movement over the entire length of the cylinder.

As noted, the angular disposition of the head, shown in dotted lines in Fig. 1, reduces the whip of the belt. The irregular edge of the belt eliminates any edge markings produced by a belt having a straight edge.

The practice of the method is as follows:

In the manufacture of these photoengraving cylinders, the cylinders are duly coated with copper of the proper diameter and polished. The surface must be thoroughly free of scratches. After the cylinders are finished, they are then processed to engrave the pictures, or the like, onto them by a chemical process known in the art. Necessarily, this engraving penetrates beneath the outer surface of the cylinder in the parts that are to be inked. Ink is then distributed over the cylinders and the excess is scraped off by the rotating cylinders against a knife blade that is contiguous to the normal diameter of the cylinder but, of course, spaced outwardly from the portions that are engraved. This blade scrapes the ink away from the normal surface of the cylinder and leaves the engraved portions filled with ink that will print.

If there be present on the cylinders any markings or scratches, ink will be entrapped in them and will print out onto the paper. Where the polishing marks are not unidirectional and where they are at an acute angle relative to the knife blade, ink will be entrapped in them. Intersections are a particular problem, since, frequently, they are deeper even than single abrasive scratches and they also form pockets to trap the ink.

In the present method, the polishing is done by applying an abrasive in a single direction around the cylinder. More particularly, the method includes automatically passing an abrasive over the surface of a cylinder and producing such relative movements between the abrasive and cylinder as to completely polish the surface thereof by an abrasive always moved in the same direction over that surface.

Furthermore, the present method comprehends abrading the surface without applying a direct pressure against the surface. The contact between the belt and the cylinders is between the two rollers 150. Between these rollers, the belt

may yield away from the cylindrical surface in a degree determined by its tension. There is no positive head resting against the abrasive material to hold it on the cylinder. Thus, should a particle of abrasive or like material come between the belt and the cylinder, the inherent elasticity of the belt will cause the belt to yield and carry this particle of abrasive out without its digging into the surface of the cylinder.

In practicing the method, it is first proposed to traverse the surface of the cylinder with a relatively coarse abrasive. Thereafter, a buffer belt, such as shown in Figs. 15 and 16, may be employed to add the final finish. The irregular surfaces provided by the pads on the buffer belt break up any streaking effects of abrasive dust, and prevent clotting of particular parts of the belt, with resultant scratching.

The buffing action need not necessarily be used. Sometimes in place of using a second belt, turpentine or like material can be applied to the original belt after it has done its first polishing. This turpentine causes the belt to collect particles of copper upon further running, which copper collects on the belt between the interstices of the abrasive, to reduce the abrading effect, and to produce a burnishing one.

This process not only produces a far superior surface on the cylinder, but also does so in a very much shorter time than has formerly been required. With heretofore known means, it has required, for example, three hours for polishing a cylinder of a certain type. With the present process, a superior surface can be put on the cylinder in from twenty to thirty minutes.

From the foregoing, it may be seen that a new and greatly advantageous method has been provided. It is known that more or less similar means have been used for polishing other surfaces, but never in connection with and following the steps of the present method. Furthermore, a machine has been provided disclosing one most advantageous way of producing the method.

What is claimed is:

1. In a polishing machine for photoengraving cylinders, a bed, means to hold the cylinder thereon, a head, an endless belt polishing medium on the head, means driving the belt across the surface of the cylinder, and the belt having an irregular edge to avoid edge markings on the cylinder.

2. In a mechanism of the kind described, a bed, a head mounted for movement across the bed, a frame mounted on said head, said frame extending across the bed, rollers, one at each end

of the frame, an endless belt polishing medium mounted on said rollers, means supporting the frame at one end on the head for pivoting movement about a horizontal axis, and screw means interengaging between the head and the frame for pivoting the frame.

3. In a mechanism of the kind described, a bed, a head mounted for movement across the bed, a frame mounted on said head, said frame extending across the bed, rollers, one at each end of the frame, an endless belt polishing medium mounted on said rollers, means supporting the frame at one end on the head for pivoting movement about a horizontal axis, and screw means interengaging between the head and the frame for pivoting the frame, said screw means including a screw, means supporting the screw on the frame against axial movement but for lateral movement to accommodate for displacement of the axis of the screw relative to the frame when the frame is pivoted on the head.

4. In a mechanism of the kind described, a bed for supporting an object to be polished, a head on the bed extending across the object, an endless belt abrasive on the frame and movable across the object, means for directing the abrasive onto the object including two slides mounted on the head, one on each side thereof, said slides being mounted for displacement on the head, a contact means supported between the slides to act on the abrasive, and means acting on both slides at once to displace them together for adjusting said contact means.

5. In a mechanism of the kind described, a bed for supporting an object to be polished, a head on the bed extending across the object, an endless belt abrasive on the frame and movable across the object, means for directing the abrasive onto the object including slides on opposite sides of the frame, contact means supported between the slides to act on the abrasive, means mounting the slides for movement in a first plane, means moving said slides together in said first plane, means mounting the slides for movement in a second plane, and means moving the slides together in said second plane.

6. In a polishing machine, a bed to hold a cylinder to be polished, a head, an endless belt polishing device on the head and adapted to be swung over the cylinder so that the belt may traverse the surface thereof, means to limit the swinging of the head to determine the pressure of the belt on the cylinder, and means to adjust the limiting means.

FRANK E. YETTER.
